(57) **CLAIM**

The ornamental design for a hose collar, as shown and described.

DESCRIPTION

FIG. 1 is a perspective view of the hose collar.

FIG. 2 is a front view thereof.

FIG. 3 is a back view thereof.

FIG. 4 is a first side view.

FIG. 5 is a second side view.

FIG. 6 is a top view thereof; and,

FIG. 7 is a bottom view thereof.

The broken line outline of the hose with a symbolic break illustrate the environment associated with the hose collar and form no part of the claimed design.

1 Claim, 2 Drawing Sheets
